(57) **CLAIM**

The ornamental design for heel for footwear, as shown and described.

DESCRIPTION

FIG. 1 is a front perspective view of a heel for footwear showing my new design;

FIG. 2 is a left side view thereof;

FIG. 3 is a right side view thereof;

FIG. 4 is a rear view thereof;

FIG. 5 is a front perspective view of a second embodiment of FIG. 1;

FIG. 6 is a left side view of FIG. 5;

FIG. 7 is a right side view of FIG. 5;

FIG. 8 is a rear view of FIG. 5;

FIG. 9 is a front perspective view of a third embodiment of FIG. 1;

FIG. 10 is a left side view of FIG. 9;

FIG. 11 is a right side view of FIG. 9; and,

FIG. 12 is a rear view of FIG. 9.

The broken line showing of the body of the footwear and sole is for illustrative purposes only and forms no part of the claimed design.

The stippling is meant to indicate a textured surface (such as fabric or leather), while the linear shading is meant to indicate a relatively smooth surface (such as metal).
